UNITED STATES PATENT OFFICE.

CARL F. BRAUN, OF SAN FRANCISCO, CALIFORNIA.

WATER-COOLING TOWER.

Application filed April 23, 1920. Serial No. 377,277.

To all whom it may concern:

Be it known that I, CARL F. BRAUN, a citizen of the United States, residing at city and county of San Francisco and State of California, have invented a new and useful Improvement in Water-Cooling Towers, of which the following is a specification.

This invention relates to water cooling towers.

10 It is the principal object of the present invention to provide a water cooling tower of the atmospheric type which is of simple construction and so designed as to be formed from composite units formed at the plant and adapted to be readily assembled at the point of installation, thereby insuring that the erection process may be rapidly carried on and that the cooling tower when finished will be of a predetermined standard design.

20 The present invention contemplates the use of a main frame and a plurality of side and corner units adapted to be assembled relative to the main frame in a manner to produce a cooling tower of any predetermined capacity.

The invention is illustrated in the accompanying drawings, in which:

Figure 1 is a view in side elevation showing a tower of the present construction with parts broken away to more clearly show the structural details.

Fig. 2 is a view in plan showing the completely assembled tower.

Fig. 3 is an enlarged view in section 35 through the feed and distributing troughs as seen on the line 3—3 of Fig. 2.

Fig. 4 is a view in elevation showing one of the corner units.

Fig. 5 is a view in elevation showing one 40 of the side units.

The present invention is particularly concerned with a cooling tower of the general type shown in my Patent, No. 1,334,515, issued March 23, 1920, and entitled "Water cooling tower." In that patent, however, the cooling tower is gradually built up from slat and frame members while in the present instance the frame is originally built, thereafter the louvres are formed from corner and side louvre sections built at the manufacturing plant and assembled at the erection locality.

In the drawings, 10 indicates vertical corner posts forming the vertical frame members upon which horizontal frame members 11 are supported. The corner posts and

frame members are here indicated as being formed of wood. Suitable diagonal braces, 12 are used to secure the corner posts in rigid relation to each other while the horizontal frame members 11 are adapted to cross each other at the posts and to be secured thereto. Attention is directed to the fact that the horizontal members project a considerable distance from the vertical faces of the posts, thus forming out bearing supports for the louvres 13. These louvres are of composite construction and comprise side louvre sections 14, and corner sections 15. Each of the sections consists of grooved end rails 16 into which the opposite ends of the louvre boards 17 project. It is preferable that the louvre boards shall overlap each other at their joints, thereby providing a substantially water tight wall which will prevent leakage of the water in the cooling tower and also shield the central portion of the tower from the action of wind. The louvre walls extend upwardly and outwardly at angles of substantially 45° while the sections are bolted by their lower edges to the horizontal frame members 11 at points near the posts 10 and by their upper edges to the outer ends of the horizontal frame members, thus being supported in their inclined positions. In this manner the upper edges of the louvre walls will conceal the lower edges of the super adjacent walls, thus forming a complete wind break while permitting free circulation of air between the various walls. In the drawings the cooling tower is formed from single sections 14 and 15, the sections 14 being secured along the sides of the tower, and between the horizontal frame members while the sections 15 are secured diagonally across the corners of the tower and between the projections of the horizontal frame members crossing at the posts. If the length of section 14 is excessively great intermediate boards 18 may be used to secure the various louvre boards 17 in position and prevent them from sliding or sagging.

Mounted upon the horizontal frame sections and within the area defined by these sections and the corner posts are a plurality of superimposed decks. The uppermost of these decks is a distributing deck 19 secured at the top of the frame and formed of a plurality of slats extending parallel to each other and disposed in spaced relation to each other. This construction is more completely disclosed in my patent as men-

J. SCHEMINGER, JR.
LIQUID FUEL FEEDING MEANS.
ORIGINAL FILED AUG. 27, 1919,

2 SHEETS-SHEET 2

UNITED STATES PATENT OFFICE.

JOHN SCHEMINGER, JR., OF PROVIDENCE, RHODE ISLAND.

LIQUID-FUEL-FEEDING MEANS.

Application filed August 27, 1919, Serial No. 320,213. Renewed September 14, 1922. Serial No. 568,283.

To all whom it may concern:

Be it known that I, JOHN SCHEMINGER, Jr., a citizen of the United States, residing at Providence, in the county of Providence and State of Rhode Island, have invented 5 certain new and useful Improvements in Liquid-Fuel-Feeding Means; and I do hereby declare the following to be a full, clear, and exact description of the invention, such as will enable others skilled in the art to which it appertains to make and use the same.

This invention relates to devices for feeding liquid fuel burners and particularly rotary oil burners.

The primary object of the invention is to provide means for effecting a steady and uniform feed or flow of the liquid fuel from a pump to the burner or other device with 20 which my invention may be used unaffected by the pulsations of the pump, which, in pump-fed liquid fuel burners as heretofore constructed seriously interferes with the operation of the burner resulting at times 25 in extinguishing the flame.

In the operation of pump-fed rotary oil burners, it is difficult, if not impossible, to prevent the flame from becoming extinguished when the liquid fuel is conducted 30 direct from the pump to the burner, because of the agitation or pulsatory action of the pump-piston on the moving column of liquid, and the primary object of my invention is to overcome this difficulty and provide means whereby a portion of the moving 35 column of liquid fuel in its passage from the pump to the burner is separated from the major portion and the air contained therein and caused to descend and 40 flow quietly to the burner or other device unaffected by the agitation or pulsations produced by the pump-piston, while the larger portion is caused to pass in a continuously ascending column to a point from 45 which it may descend or be delivered into a receiving tank or vessel and returned therefrom to the source from which it came.

The invention will first be hereinafter more particularly described, with reference 50 to the accompanying drawings, which are to be taken as a part of this specification, and then pointed out in the claims at the end of the description.

In said drawings—

Fig. 1 is a vertical sectional elevation of

an oil separating and quieting device or apparatus embodying my invention;

Fig. 2 is a transverse section of the same taken on the line 2—2 of Fig. 1, and Fig. 3 is a vertical sectional elevation of an apparatus embodying my invention, showing a rotary pump interposed in the pipe connections between the oil tank or source of supply and the oil separating and quieting device; the pump being of the form shown 60 in my application, Serial No. 315,983, filed August 7, 1919, for improvements in thermally controlled rotary oil burners.

Referring to said drawings, in which the same reference letters are used to denote 70 corresponding parts in different views, the letter A denotes the oil separating device, or separating and settling chamber, which is interposed in the pipe connections leading from the pump P to the burner or other 75 device (not shown), the pump being connected with an oil tank or other source of liquid fuel supply through the pipe p and discharging into a pipe B which conducts the liquid into the receiving chamber a of 80 the separator. The casing of the separator is preferably of diamond-shaped form and oblong in cross-section, as shown in Fig. 2, having one reduced end-portion at the base thereof and the other reduced end at the 85 top. A vertical partition C extends upwardly from the bottom or reduced end-portion of the casing to a point near its top, thus forming a receiving chamber at one side of said partition and a settling 90 chamber at the other side thereof. At the bottom of the settling chamber a¹ there is an outlet opening with which is connected a pipe D into which the quieted liquid is discharged. Said pipe D is connected with 95 the feed pipe for supplying fuel to the burner or other device. A portion of the liquid entering the receiving chamber a is forced upwardly by the pump into and through a pipe E at the top of the separator, while a smaller portion flows into the 100 settling chamber a¹. As the oil passes over the top of the partition and begins to descend into the chamber a¹ it is broken up sufficiently to cause a separation of the 105 globules of air contained therein and is thereby condensed and caused to pass to the burner in a quiet or non-turbulent and steadily flowing stream. The pipe E has a check valve therein, at e, to prevent back flow 110

when the pump is stopped. This pipe extends upwardly to a predetermined point so that the major portion of the liquid passing through the separator is caused to ascend high enough to create sufficient back pressure opposed to and tending to counteract the pressure of the pump, to accomplish the desired separation and quieting of the minor portion of the liquid which flows into the settling chamber, and such back pressure acting on the lesser portion of liquid in the settling chamber effects the passage thereof quietly, continuously and evenly to the burner or other device unaffected by the pulsations or irregular movements of the pump piston or pistons. The diamond-shaped form of the separator casing is preferred, though not indispensable, as a cylindrical, square or other form may be used, and various other changes may be made in the details and arrangement of parts without departing from the spirit and scope of my invention.

The operation of the apparatus will be readily understood from the foregoing description, when taken in connection with the accompanying drawings. As will be seen, the oil under pressure is conducted into the receiving compartment of the separating apparatus and the major part thereof is forced into a continuously ascending column through and out of the pipe E, and thence into a receiving tank or container or back to the source of supply while a part of the oil is carried over the top of the partition C and caused to descend and flow quietly to the burner or other device unaffected by the agitation or pulsation of the pump to which the ascending column of liquid is subjected.

Having thus described my invention, what I claim as new, and desire to secure by Letters Patent is:

1. Oil feeding means comprising a supply

tank, a circulating system including a pump and means for separating the oil and causing the larger portion to return to the tank while the lesser portion is caused to pass quietly and evenly to a burner or other device unaffected by the pulsations of the pump. 45

2. In combination, a liquid fuel supply tank, a pump and means whereby the liquid fuel is drawn from said tank by the pump and a portion thereof separated and freed from air and caused to flow quietly and evenly to a burner or other device while the major portion is caused to ascend to a predetermined point from which it is conducted back to said tank; the ascending column of liquid being adapted to exert back pressure 60 acting on the lesser portion to effect the passage of the latter to the burner or other device unaffected by the pulsations of the pump. 50

3. Liquid fuel feeding means for a burner 65 or other device, comprising a tank or source of supply, a pump, a separating and quieting apparatus, and pipes connecting said pump with said tank and said apparatus, whereby the oil drawn from the tank is divided into unequal portions and the larger portion caused to move in an ascending column to a predetermined point and then return to the tank, the ascending column being adapted to exert back pressure acting 75 on the smaller portion and with the aid of the pump causing said smaller portion to pass quietly and evenly to the burner or other device unaffected by the pulsations of the pump. 70

In testimony whereof I affix my signature in the presence of two witnesses.

JOHN SCHEMINGER, JR.
